of Delaware

Application May 21, 1953, Serial No. 25,162

Term of patent 14 years

(Cl. D15—8)

To all whom it may concern:

Be it known that I, Joseph E. Adkinson, a citizen of the United States, residing in York, in the county of York and State of Pennsylvania, have invented a new, original, and ornamental Design for a Chair, of which the following is a specification, reference being had to the accompanying drawing, forming part thereof.

In the drawing:

Fig. 1 is a perspective view of a chair viewed substantially from the front thereof and embodying my new design.

Fig. 2 is a perspective view of the chair shown in Fig. 1 as viewed substantially from one side thereof.

I claim:

The ornamental design for a chair, as shown.

JOSEPH E. ADKINSON.
